UNITED STATES PATENT OFFICE.

GERGELY ORDOG, OF ELLIS ISLAND, NEW YORK.

ELEVATOR SAFETY STOP.

Application filed November 24, 1924. Serial No. 751,737.

This invention relates to safety devices for elevators that are applied to the latter to prevent accident in the event of the supporting cable breaking, the invention having for an object the provision of a simple and efficient safety device of this sort.

For further comprehension of the invention, and of the objects and advantages thereof, reference will be had to the following description and accompanying drawing, and to the appended claim in which the various novel features of the invention are more particularly set forth.

Fig. 1 of the drawing is a side view showing my safety device applied to an elevator.

Fig. 2 is an end view thereof.

Fig. 3 is a plan view.

Fig. 4 is a fragmentary transverse sectional view taken on the line 4—4 of Fig. 2 and showing the parts in a different position.

The elevator to which my invention is here shown as applied is of the freight carrying type and comprises an open frame including a longitudinal top bar 10 that has fixed to the ends thereof the brackets 11 which carry flanged rollers 12 that engage the vertical guide posts 13. This bar 10 has fixed thereto transverse elements such as 15 from which depend the members 16 that support a platform 17, this platform being suitably arranged at its ends to engage the guide posts 13. Extending freely through a suitable vertical aperture formed in the bar 10 midway between the ends of the latter is a bolt 20 having a flattened and vertically elongated head 21 on its upper end, this head having connected thereto the cable 22 by which the elevator is suspended. The bolt 20 has a nut 23 on its lower end and between this nut and the bottom of the bar 10 an expansion spring 24 is coiled around the bolt and forms a resilient support for the elevator.

Rotatably supported in the transverse elements 15, and extending parallel to the bar 10 one on each side thereof, are the shafts 28. These shafts have pawls 29 fixed to their opposite ends that are adapted to engage ratchet toothed racks 30 formed on opposite sides of the guide posts 13, the teeth of these racks facing upwardly, so that the elevator is supported thereby when the

pawls engage therewith in the event of the cable 22 breaking. The pawls are normally urged into engagement with the racks 30 by means of the helical springs 32 that are coiled around the shafts 28. These springs are attached at one end to the transverse members 15 before mentioned, and at their opposite ends to arms 33 fixed to the shaft 28, so as to impart a rotary urge to the latter.

The shafts 28 have mounted thereon, midway between their ends so as to be juxtaposed to the bolt 20, the arms 35 that diverge upwardly from one another and have pivotally connected to their upper ends the links 36 that are connected also to the head 21 of the bolt 20, the links inclining upwardly from the arms 35 to engage the head 21 when the parts are in normal position, so that downward movement of the bolt when the cable 22 breaks acts to impart a rocking movement to the arms 35 to swing the pawls 29 against the racks. This rocking movement of the shafts 28 may be limited by means of the arms that engage the bar 10. In the event of the cable 22 breaking, the springs 24 and 32 act in conjunction to move the bolt 20 downward with respect to the elevator, thus swinging the pawls 29 into engagement with the racks 30 and preventing the elevator from falling. It will be understood that the spring that acts on the cable is of sufficient strength to move the latter irrespective of the point at which the break may occur. It will be clear that upon a break occurring in cable 22, the spring 24 will come to action and move rod 20 causing the links 36 which are connected to the head 21 of the rod or bolt 20 to assume the position illustrated in Figure 4, and to rotate the shafts 28 in conjunction with the rotating action of the springs 32 so that the pawls 29 engage the rack 30 as illustrated in Figure 4.

Having thus described my invention, what I claim as new and desire to protect by Letters Patent of the United States is as follows:

In a device of the class described, an elevator car, shafts mounted thereon, pawls fixed to the outer end of the shafts, racks fixed adjacent the elevator car, the said pawls being engageable with the racks, a cable connected to the elevator car for oper-

ating purposes, means associated with the cable and the elevator car for engaging the pawls against the racks upon the breaking of the cable, arms fixed to the said shafts, and springs co-axial on the shafts, one end of each spring being fixed to a stationary part of the elevator car, and the other end

to each arm, the said springs normally helping to urge the pawls into engagement with the racks.

10

In testimony whereof I have affixed my signature.

GERGELY ORDOG.
